Primary Examiner — Randall Gholson

(57) **CLAIM**

The ornamental design for a chinstrap connector for safety helmet, as shown and described.

DESCRIPTION

FIG. 1 is a top perspective view showing the new design for a chinstrap connector for safety helmet;

FIG. 2 is a top view thereof;

FIG. 3 is a side view thereof;

FIG. 4 is a bottom view thereof;

FIG. 5 is a front view thereof;

FIG. 6 is a back view thereof; and,

FIG. 7 is a bottom perspective view thereof.

1 Claim, 2 Drawing Sheets
